CLAIM

The ornamental design for a removal tool, as shown and described.

DESCRIPTION

FIG. 1 is a bottom perspective view of a removal tool showing our new design;

FIG. 2 is a left side elevational view thereof, the right side elevational view being identical to FIG. 2;

FIG. 3 is a front elevational view thereof, the rear elevational view being identical to FIG. 3;

FIG. 4 is a top plan view thereof; and,

FIG. 5 is a bottom plan view thereof.

The broken lines represent unclaimed subject matter and form no part of the claimed design.
